UNITED STATES PATENT OFFICE.

JOHN JOFEH, OF WALTHAMSTOW, ENGLAND.

COIN-FREED APPARATUS.

SPECIFICATION forming part of Letters Patent No. 763,289, dated June 21, 1904.

Application filed July 14, 1902. Serial No. 115,560. (No model.)

To all whom it may concern:

Be it known that I, JOHN JOFEH, engineer, a subject of the Czar of Russia, residing at 3 Cleveland Park avenue, Walthamstow, in the 5 county of Essex, England, have invented certain new and useful Improvements in or Relating to Coin-Freed Apparatus, of which the following is a specification.

The object of my invention is to construct 10 a new or improved form of coin-freed amusement or skill apparatus adaptable for use of one player or operator or for the simultaneous use of more than one player or operator, said apparatus being self-setting and provided with 15 means for delivering a prize to the successful player or operator.

In the accompanying drawings, Figure 1 is 20 a front view of the apparatus mounted in a glazed case. Fig. 2 is a rear elevation. Fig. 20 3 is a plan of the tracks. Fig. 4 is a modified construction and arrangement of a portion of the apparatus. Fig. 5 is a modification of 25 coin-controlling device. Fig. 6 is a sectional side view of a portion of Fig. 2 on the line 25 A A. Fig. 7 is a plan view of a coin-operated releasing device. Fig. 8 is a plan view of the coin-delivering mechanism.

According to my invention I mount in a suitable glazed case *a* a pictorial scene, 30 preferably depicting a straight or curved hill or incline, up which one or more figures, cyclists, or motor-carriages or other moving objects, such as *b*, are propelled.

By way of example I will describe my invention as applied to two cyclists arranged 35 to climb a hill and operated by two players. I fit a pair of inclined bars or rods *c* behind the scene and mount upon each a suitable carriage *d*, to which a model of a cyclist *b* is 40 connected. At the upper end of the inclined bars *c* I fit a spindle *e*, with pulleys *e'* mounted thereupon.

f f' are bucket-wheels or turbines or the like fixed to spindles *g g'*, and *h h'* are jets 45 connected by rubber or other pipe *i* to external mouthpieces, as *k*, Fig. 1, so that on the operators blowing into said tubes the turbines *f f'* and their spindles are revolved. Cords or the like *ss'* are attached to the spindles *g g'* 50 and also to the carriages *d d*, before men-

tioned, passing over the pulleys *e'*, whereby as the cords are wound up the bicycles are drawn up the incline.

Each operator inserts a coin in his respective slot in the case and each coin passes down 55 a chute, from the end of which it falls into its respective coin-receptacle *l*, which may be integral with said carriage, as in Fig. 2, or pivoted thereto, as in Fig. 5. The front of 60 said coin-receptacle is open, and in the case of Figs. 2 and 3 the bottom is recessed to receive a pin *m*, (which projects into both coin-receptacles *l*, as shown in Fig. 7,) attached to a weighted lever *n*, so that unless a coin is 65 inserted into both coin-receptacles, whereby to disengage the lever, the carriage cannot be moved up the incline. In Fig. 5 the weight 70 of the coin depresses the receptacle *l* below the end or edge of the bar or rod *c*, and so releases the carriage.

Under the inclined bar or rod *c* I fit a correspondingly-inclined table *O*, Fig. 2, upon which the coin rolls within the coin-receptacle *l* as it travels up the incline. At a suitable position on said table I fit a short inclined plane 75 or ratchet-tooth, such as at *o'*, so arranged that the coin in rolling up the inclined table rises over said tooth; but should the operator not succeed in causing the figure to travel to the top of the hill the return movement (by gravity) brings the coin against the vertical side 80 of the tooth, retaining it until the coin-receptacle has descended, when the coin drops into the money-box. In some cases more than one tooth or short inclined plane may be fitted on 85 the table. Similarly in the case of the receptacle being pivoted to the carriage, as in Fig. 5, the same effect is produced by pins or studs *c'*, attached to the rod or bar *c*.

If the apparatus is made for only one operator and he succeeds in gaining the top of the hill, the coin falls from the upper end of the inclined table into a chute, from which it falls into an external tray or is caused to deliver a prize or a check. In the case of two 95 operators the coins are controlled as herein-after described.

The roadway may be provided with one or more obstacles—such as a model of a revolving windmill, turnstile, opening and shutting 100

gates, skipping-rope, or a model of a policeman waving his arms, as shown at *p*—the motion being transmitted thereto by the falling coin with or without intermediate power 5 mechanism or by the force applied by the operator, the latter case being shown in Figs. 2 and 6 of the drawings.

The figure *p*, which is hollow, is fixed between the two tracks *c* and is provided with 10 arms *p'*, pivoted at *p*² and connected by rods or wires *p*³ to a pair of independent crank-spindles *q q'*. The latter carry pulleys *r r'* and are supported in suitable bearings. The cords *s s'* are passed over said pulleys *r r'*, so 15 that on the bucket-wheel being revolved the pulleys *r r'* are also revolved, and thus cause the arms *p'* to move up and down. The bicyclists *b* are blocked when the arms are up, and the players have consequently to judge 20 the pace and opportunity for passing the obstacle. It will be understood that the position of the arms *p'* relatively to the carriages is variable, according to the force applied by the operators, the cords slipping occasionally 25 upon the said pulleys.

The propelling force may be arranged to rotate a wheel or wheels of and so propel the model vehicle. In the case shown in Fig. 4 the spindle of one of the wheels *t* is extended 30 through a slot to the back of the scene and is connected with a bucket or turbine wheel *f*, which is carried by the wheels *t*, the air-jet *h* being connected with the mouthpiece by means of flexible tubing *i*', or the propulsion 35 may be effected by winding a cord *s* upon the spindle of the bucket-wheel *f*, as indicated by the dotted lines.

In order to allow of the delivery of the coin to the successful player or operator 40 where two participate in a race or contest, I provide two sets of slots arranged in a cruciform manner, as shown in Figs. 2 and 8, two being "losing" slots *u*, leading into the till or money-box, and two being "winning" slots 45 *v*, leading to a delivery spout or apparatus. A double coin-carrier *w* is pivoted at the center of the cross-slots, so that when one end or the other is moved by the winning figure or moving object one coin is returned to the 50 winner (or a check or goods delivered) and the other coin is precipitated into the till. The double coin-carrier *w* is arranged to be self-acting after use (by means of a tail-spring *w'* or other device) and is, as will be understood, situated at the lower end of a twin 55 coin-chute, such as *v*², Figs. 2 and 3. The double coin-carrier *w* is connected with any suitable trigger mechanism or other device located in the path of the moving object, so 60 that whichever object arrives at the top first depresses or pushes aside or otherwise operates the connection *x* with a coin-carrier *w* to bring the latter opposite the chutes *u* and *v*.

I claim—

65 1. In a coin-freed lung-testing apparatus,

the combination with an air-tube, of a bucket-wheel or turbine adapted to be revolved by blowing through said tube, a flexible medium operatively connected to said bucket-wheel and adapted to be wound up thereby, an inclined track, a carriage mounted upon said track and connected to said flexible medium, a coin-carrier attached to said carriage, locking mechanism normally preventing movement of said carriage and adapted to be freed 70 from engagement therewith by the insertion of a coin in said carrier, and means whereby the coin is removed from said carrier by the return downward movement of said carriage, substantially as set forth. 80

2. The combination with an inclined track provided with a carriage adapted to travel thereon, and means for drawing the carriage up said track, of a pivoted coin-carrier upon said carriage adapted to lock the same against 85 movement and to release the carriage upon the insertion of a coin in said carrier, projections upon the under side of said track against and over which the coin is caused to travel in its carrier one or the other of said 90 projections being adapted to dislodge the coin from the said carrier upon a return or downward movement of the carriage over said track and to permit the coin to fall and said coin-carrier being adapted to engage with one 95 or the other of said projections to prevent further upward movement of the carriage.

3. The combination with an inclined track provided with a carriage adapted to travel thereon and means for drawing the carriage up the track of the coin-carrier integral with 100 said carriage, an inclined fixed table arranged beneath said carrier in the line of movement of the carriage and adapted to support the coin in said carrier, said table having a projection adapted to dislodge the coin from said carrier upon a downward movement of the carriage, and means for locking the carriage and adapted to be disengaged therefrom upon 105 the insertion of a coin in said carrier. 110

4. In an apparatus of the character described, the combination with an air-pipe and an inclined track, of a model vehicle adapted to travel over said track, a carriage or frame suspended therefrom, a flexible tube attached 115 to said carriage or frame and connected with said air-pipe, a bucket-wheel or turbine mounted in said frame and adapted to be rotated by blowing through said air pipe and tube, means whereby the rotation of the bucket-wheel 120 causes the vehicle to travel up said inclined track, locking mechanism for normally preventing movement of said carriage and adapted to be operated to unlock the carriage on the insertion of a coin. 125

5. In a device of the character described, the combination with an inclined track provided with a pair of models adapted to be drawn over said track, an obstacle interposed in the path of each model and having a movable portion, 130

means for continuously operating the movable portion of said obstacle to cause it to intermittently block and free the path of said models, and locking mechanism adapted normally to prevent movement of said models and adapted to be released from engagement therewith upon the insertion of a coin.

6. In a coin-freed lung-testing apparatus, a pair of coin-chutes, a double coin-carrier pivotally located at the lower end of said chutes and arranged to coöperate with the double set of openings provided below said double carrier, movable members adapted to be independently operated by blowing into the apparatus, means interposed in the path of said

movable members for turning said carrier upon its path to discharge the coins inserted therein into one or the other of said double openings, one of said openings being arranged to deliver a coin falling through the same external to the apparatus, and means for resetting said double coin-carrier as set forth. 20

In testimony whereof I have hereunto set my hand in presence of two subscribing witnesses.

JOHN JOFEH.
